CHAIR OR SIMILAR ARTICLE

Floyd O. Bohnett, Santa Barbara, Calif.

Application February 8, 1950, Serial No. 7,791

Term of patent 14 years

(Cl. D34—15)

To all whom it may concern:

Be it known that I, Floyd O. Bohnett, a citizen of the United States, residing at Santa Barbara, State of California, have invented a new, original, and ornamental Design for a Chair or Similar Article, of which the following is a specification, reference being had to the accompanying drawings forming a part hereof and in which:

The single figure is a perspective view of a chair or similar article showing my new design.

The characteristic feature of my new design for a chair or similar article resides in the provision of disproportionately elongated taper pins arranged through the reduced ends of the round, horizontally disposed members of said article. The drawing has been shaded to show contrast in appearance.

I claim:

The ornamental design for a chair or similar article, as shown and described.
